DESIGN FOR A FISHING REEL FRAME

Stephen G. Hirsch, Philadelphia, Pa., assignor to
Ocean City Manufacturing Company, Phila-
delphia, Pa., a corporation of Pennsylvania

Application February 21, 1945, Serial No. 118,076

Term of patent 14 years

(Cl. D31—4)

To all whom it may concern:

Be it known that I, Stephen G. Hirsch, a citizen
of the United States, residing in Philadelphia,
county of Philadelphia, State of Pennsylvania,
have invented a new, original, and ornamental
Design for a Fishing Reel Frame, of which the
following is a specification, reference being had
to the accompanying drawing, forming part
thereof, in which:

Figure 1 is a perspective view of a fishing reel
frame showing my new design; and

Figure 2 is an end elevation.

The characteristic features of the design are
shown in full lines in the drawing.

I claim:

The ornamental design for a fishing reel frame,
as shown and described.

STEPHEN G. HIRSCH.
